(57) **CLAIM**

The ornamental design for a remote control, as shown and described.

DESCRIPTION

FIG. 1 is a front, bottom and right-side perspective view of a remote control showing the new design;

FIG. 2 is a rear, bottom and right-side perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

Please note that the broken lines, if any, shown in the drawings represent portions of the remote control that are included for illustrative purposes only and form no part of the claimed design.
